BULLET SIZING AND/OR LUBRICATING MEANS

William G. Stevens, Jr., Sykesville, Md.

Application September 27, 1946, Serial No. 699,859

10 Claims. (Cl. 86—19)

1

This invention relates to bullet sizing and lubricating devices, and more particularly to improvements in the mechanism disclosed in my Patent No. 2,403,032, dated July 2, 1946. The apparatus herein described is suitable for carrying out the method of sizing and lubricating bullets as set forth in said patent.

The present invention, unlike its predecessors, employs an active member adapted to move against a plurality of plungers or pistons in contact with a stationary member to force grease from movable reservoirs in different directions, directly, and circumferentially even therearound into the groove or grooves of a bullet during the lubricating operation. In accordance with this embodiment of my invention, I am enabled to avoid a difficulty which has been heretofore encountered by the prior art mechanisms of this general character. This difficulty being the inability of said mechanisms to continually fill the bullet grooves evenly and uniformly during the greasing operation. It is well known that a great number of bullets passed through the known devices will show some bullets with grooves not quite full of grease, the lubricant streams will appear to have passed around the bullet groove or grooves from a single point in two directions and not quite have flowed together at a diametrically opposite point. High pressures applied to the lubricant during the greasing operation will not overcome this difficulty but only make matters worse; the cause of this objectionable difficulty will be made apparent from the explanation immediately following.

In conventional practice it has been customary to provide the prior art devices of this general character with grease feeding means which force lubricant into a bore through a duct or lubricant passageway. The conventional die means usually consists of a single die having grease feeding channels extending circumferentially and also through the wall thereof. This die is contained within said bore with its grease feeding channels in communication with said duct or lubricant passageway. During the greasing operation, pressure is brought to bear upon the lubricant from a source and is forced through the duct, and the grease feeding channels of the die, to the groove or grooves of a bullet positioned within an elongated passage extending axially through the die. As a result, lubricant is forced directly on the side of the bullet nearest the duct which conveys lubricant from the source to the grease feeding channels of the die, while the other side of the bullet is greased only by lubricant which

5

has been forced against the bore and then back through the channels of the die. That is, the grease under pressure, following the lines of least resistance, reaches the nearest side of the bullet by direct paths while the opposite side of the bullet is reached only by lubricant forced around the bullet or which has been forced by back pressure through the grease feeding channels of the die. Examination of a number of bullets which have been processed by the known devices of this general character will show many bullets unevenly lubricated with grooves not quite full. On still closer inspection it will be found that the unlubricated portions of the grooves were opposite the previously referred to duct or lubricant passageway. Also, an examination of the die means will show that the lubricant opposite the duct through which fresh grease entered, said means has been compacted and become more viscous than the incoming lubricant. This packed and accumulated lubricant acts to resist the flow of fresh lubricant around the bullet as well as the back pressure generated within the grease feeding channels of the die means. In fact, the very hard types of lubricant containing generous proportions of Carnauba wax cannot be used in devices of this general character. In general, better results are obtained from hard lubricants than from the softer mixtures. There is a wide divergence of opinion as to the effect of lubrication on bullets, but, the fact remains, that hard lubricants have a higher melting point, do not collect dirt, age well, and do not blow out of the grooves easily and rub dry toward the muzzle when used in rifles. The soft mixtures are inexpensive and easy to apply. The terms "hard" and "soft" lubricants, as just used, are relative; and, as previously stated, the very hard or extreme types of lubricants cannot be forced through the grease feeding channels of the conventional die means.

10

In order to provide novel means for compressing a good quality hard lubricant (not an extreme type lubricant) evenly into the grooves of bullets, it is proposed, according to the present invention, to make use of a plurality of ducts or lubricant passageways (each duct in communication with a separate source of lubricant) and arranged in such manner that the lubricant is conveyed directly, in different directions, and simultaneously into the groove or grooves of bullets in a manner soon to be explained. This novel means avoids the compacting and accumulation of lubricant in the die means.

15

Another object of my invention is to provide

2

new and improved means for automatically compressing lubricant into the groove or grooves of a bullet at the time said bullet is properly positioned within the die means. The compressing of lubricant into the groove or grooves of the bullet being accomplished by moving the entire mechanism against a plurality of plungers or pistons in contact with a stationary member.

Another object is to supply such mechanism with novel means for regulating or controlling the discharge capacity of the ducts or passageways connecting the sources with the die means so that a certain amount of lubricant is conveyed to the die means by the feeding means during a greasing operation.

Another object of my invention is to provide new and improved means for spacing the adjacent ends of the dies which function to form an annular lubricant chamber in order to regulate or control the size of such chamber.

Other objects of my invention are the provision of means for indicating the amount of lubricant contained within the reservoirs; the provision of means to oppose the movement of the plurality of plungers or pistons slidably fitting within the lubricant reservoirs in order to prevent the discharge of grease before the bullet is properly positioned within the die means; the provision of a bullet sizing and lubricating device which is reliable and fast in operation, simple in its construction, and whereby the bullets will be more accurately sized and more evenly lubricated than with the known devices of this general character.

The foregoing and other objects, features, and advantages will be clear from the following description in connection with the accompanying drawings, in which:

Fig. 1 illustrates in side elevation, with some parts in section, or broken away, an apparatus which will serve as an example of the principles of construction and operation in accordance with the invention.

Fig. 2 is an enlarged sectional view taken on the line 2—2 of Fig. 1.

Fig. 2a is a longitudinal diametrical sectional view of one of the dies with the bore thereof exaggerated to indicate that it tapers away from its mouth.

Fig. 3 is a view taken on the line 3—3 of Fig. 1.

Fig. 4 is an enlarged view of a detail illustrating braking mechanism for one of the lubricant cylinders.

Fig. 5 is a view similar to the upper portion of Fig. 2 but showing the bullet propelling punch in lowermost position.

Fig. 6 is a side elevation of a portion of a known type of reloading tool with a modification of my apparatus mounted thereon.

Fig. 7 is a sectional view taken on the line 7—7 of Fig. 6.

Referring first to the embodiment of the invention illustrated in Figs. 1 to 5, inclusive, 8 designates a horizontally disposed base or supporting frame comprising angle iron spaced side bars 9 rigidly connected together at one end by an inclined cross bar 10 provided with apertures 11 for a purpose hereinafter described. The opposite ends of the side bars are secured together by a stationary shaft 12 on which is pivotally mounted a frame 13 comprising side bars 14 and 15, rigidly connected by cross bars 16 and 17.

The frame 13 is pivotally connected at its upper end to a body 18 having trunnions 19 and 20 journalled in apertures 21 in the side bars of the frame.

The body is provided midway between its length with a threaded aperture or bore 22 which extends through the body so as to receive at its lower end a hollow threaded plug 23 having an internal shoulder 24 on which a tubular die or bullet grasping member 25 rests. The upper end of the aperture 22 is closed by a tubular threaded plug 26 having an internal shoulder 27 on which rests a tubular die or bullet grasping member 28. A third tubular die 29 is arranged in the bore of the part 26 and rests on the die 28, and both dies 28 and 29 are secured in the plug 26 by means of a threaded tubular entrance member 30 which is in threaded engagement with the upper end 15 portion of the plug 26.

As shown in Fig. 2a, each of the dies 25, 28 and 29 is preferably provided with a bore 31 tapered away from the mouth 32 of the bore so as to compress a bullet 33 as the latter is driven successively through the dies by any suitable means, such as a punch 34 having a ram 35 at one end thereof which forms an abutment 36 adapted to contact with the entrance member 30 to limit the extent to which the punch can be driven into the bore formed by the dies. It will be observed from Figs. 2 and 5 that as the parts 23 and 26 have threaded engagement with the body 18, they can be moved toward or away from one another to vary the distance between the dies 25 and 28 30 to facilitate the introduction of lubricant or grease into the groove or grooves 37 of a bullet while the latter is in a stationary position and grasped by the dies 25 and 28. In this connection, it will be noted that when the punch is in its innermost 35 position (Fig. 5), the groove or grooves of the bullet will be properly positioned to receive lubricant.

Any suitable means may be provided to lock the parts 23 and 26 in adjusted position. For example, as shown in Fig. 3, a screw 38 may have threaded engagement with the body 18 to press upon a leather disc 39, or the like and press the latter against the threaded portion of the plug 23 or 26.

45 The body 18 is provided at diametrically opposite sides of the threaded aperture 22 with lubricant ports 40 and 41 through which lubricant may be simultaneously forced from opposite directions into the space between the inner ends of the plugs 50 23 and 26 to enter the groove or grooves of the bullet while the latter extends into the dies 25 and 28.

To supply the lubricant, the body 18 is provided with a pair of threaded apertures or bores 42 and 43 arranged in parallel relation to the aperture 22 and in close proximity thereto. Each aperture 42, 43 is provided with an adjustable threaded plug 44 having a conical extremity 45 to cooperate with the flared mouth 46 of a lubricant reservoir or cylinder 47. Each cylinder has external threads at its upper end to screw into the threaded aperture 42 or 43 and it is obvious that the tapered ends 45 of the plugs function as valves to regulate the amount of lubricant which may travel from the interior of either cylinder toward lubricant port 40, 41 with which it communicates.

Either plug 44 may be locked in adjusted position by means such as the parts 38, 39 (Fig. 3).

Lubricant may be introduced into the body and into the cylinder if desired through a port 48 arranged at one end of the body and closed by a threaded plug 49.

Each cylinder is provided with a piston or plunger 50 having a tapered extremity 51 adapted to extend into one of the apertures 11 of the sta-

tionary cross bar 10 so that the latter will act as a stop or abutment for the plungers while the cylinders move relatively thereto.

For indicating purposes, each plunger is provided at 52 with three indicating lines, at 53 with two indicating lines, and at 54 with a single indicating line. As such lines cooperate with the lower end 55 of the cylinder, it will be understood that when the lines 52 register with the lower end of the cylinder, the latter will contain a full charge of lubricant. When the lines 53 register with the end of the cylinder, the cylinder will be half full and when the line 54 coincides with the end of the cylinder, the latter will be empty.

Each cylinder is provided with a brake (Fig. 4) to normally resist movement of the cylinder relatively to the piston. The brake may consist of a band 56 surrounding the cylinder and anchored thereto by means of an impingement screw 57. An auxiliary cylinder 58 extends from the band and has a bore 59 in which a detent or axially movable lug 60 slides. The inner end of the latter extends through an aperture 61 in the cylinder and bears against the piston 50. A spring 62 is employed to yieldingly force the pin toward the piston and the compression of the spring is adjusted by means of a threaded plug 63.

By virtue of the indicating feature 52-55, the reservoirs may be filled to accommodate the very hard viscous lubricants which are difficult to force into the die means. In my above-mentioned patent, I have pointed out the advantage of having the source of lubricant in close proximity to the bullet; and by reducing the amount of lubricant in the reservoirs, the driving pistons 50 will be brought in close proximity to the bullet thereby reducing the resistance between the driving force and the die means. Of course, the duct or lubricant passageway, is fully opened by moving the control plug or valve 44 upwardly and away from the tapered mouth of the grease reservoir. From the foregoing, it is to be understood that the operator would fill the reservoirs to capacity when using the softer types of grease and reduce the amount of lubricant in the reservoirs when using more viscous types. By properly manipulating the valves 44, a variety of lubricants may be evenly and uniformly applied to bullets.

In order to balance the driving force of the pistons against the easy flowing soft lubricants, the communicating passages between the cylinders and the bullet may be restricted by moving the conical ends of the valves 44 into close proximity to the tapered surfaces of the mouths of the reservoirs. However, a condition will occur which will be explained later, whereby the driving forces of the pistons must be further reduced to prevent the discharge of grease while the bullet is being properly positioned between the dies 25 and 28. This is accomplished by means of the braking mechanism illustrated in Fig. 4. The frictional contact between the pin 60 and the piston 50 functions as a brake to retard or hold the piston against the force acting to drive the piston within the reservoir.

Reference to my prior Patent 2,403,032, will clearly explain how an annular lubricant chamber is formed between the adjacent ends of dies 25 and 28 as well as the advantages of using a plurality of dies.

In operation, after the adjustable members of the apparatus have been placed in readiness for operation, a bullet is introduced into the mouth of the entrance member 30 nose first; then, the punch 34 is employed to force the previously

inserted bullet into the bore of the die means. In such operation, the ram 35 is struck with a mallet or hammer while the entrance member 30 guides the punch while it drives the bullet ahead into the bore of the die 29. As the bullet moves into the bore of the die, it will be sized to the diameter of the most restricted section of the die, as will be evident from Fig. 2a. Due to the tapered bore of each die, it is obvious that some force will be required to force the bullet through the die. Since the body 18 which supports the die means and reservoirs 41, is not fixed, but free to move about the axis of the bar 12, it is obvious that the plungers or pistons 50 will act to oppose the force that drives the punch 34 into the apparatus. It is at this instant that the previously referred to braking means (Fig. 4) comes into play so as to hold the plungers and reservoirs in fixed relation. Of course, the force of the spring 62 is sufficient to provide a frictional resistance to overcome the force required to drive the bullet through the die 29. Also, it must be understood that the force of the spring 62 is insufficient to withstand the blows applied by the mallet on the ram 35 after the shoulder 36 thereof has come into contact with the entrance member 30 and the punch is fully inserted within the apparatus. Before the ram contacts the entrance member, the punch is moving a bullet, or bullets, which are composed of relatively soft material, such as lead, against the bores of the dies; and, this is a frictional resistance which has a definite limit or magnitude; but, once contact is made by the ram with the entrance member 30, there is a direct communication between the blows of the mallet and the reservoirs 41. Consequently, the lubricant contained within the reservoir is put under a series of pressures, and grease is pressed into the groove or grooves of a bullet that is positioned between the adjacent ends of the dies 25 and 28. Like in my prior patent, lubricant will be applied to the bullet grooves or groove in spurts. Furthermore, during the greasing operation, lubricant is forced directly on opposite sides of the bullet simultaneously. As a result, no lubricant is forced around the bullet and then pressed back by back pressure on the opposite side thereof. There is no compacting of grease on one side of the bullet since both of its sides receive grease at the same time.

As previously indicated, the problem involved in satisfactory lubrication of bullets, is the direct application of grease to all parts of the bullet grooves circumferentially, and for this purpose, I provide means to force grease into the die means in two opposite directions simultaneously. Preferably, and as disclosed herein, the lubricant is forced from separate sources. It must be remembered that lubricant forced from a single source will eventually end by backing and compacting within the die means; regardless of how many pistons have "boosted" the grease during its journey from the source of supply to the die means. In accordance with the invention, the grease is preferably forced into the die means (A) from separate sources (B) from opposite directions (C) simultaneously (D) at the time a bullet is properly positioned within the die means.

From the foregoing, it will be understood that in the general operation of the device, a bullet is placed in the mouth of the apparatus, and a suitable punch attached to an operating ram inserted; a few blows with a mallet or hammer on the ram, and the result is accomplished. The

operating punch and ram are then removed, another bullet is placed in the mouth of the apparatus and the operation repeated. Bullets are thus forced through the dies one after another and each one is properly sized and lubricated. The greasing operation, as previously explained, is entirely automatic and the bullets are lubricated when accurately positioned within the bore of the die means by frictional means that allow discharge of lubricant into the die means only when desired. The ejection of the bullets from the die 25 is also automatic.

Instead of employing a pivoted or freely movable frame to support the body or housing 18, it is obvious that such body might be fixed and supported in a stationary manner. Of course, this change will eliminate the automatic greasing operation feature; but, the novel feature of direct lubrication effect in opposite directions, could be retained. Such an embodiment could have a plurality of lubricant sources, and a plurality of plungers or pistons adapted to be struck by a mallet or hammer when it is desired to force lubricant into the die means. If such an embodiment is desired, a modification of the invention may be employed in connection with a cartridge reloader of the type shown in Patent 1,933,940, dated November 7, 1933. The embodiment illustrated in Figs. 6 and 7 will serve to disclose the principles of construction and operation in keeping with this form of the invention. The main body 20a is altered so that the axes of the reservoirs 47a and pistons 50a are perpendicular to the axis of the central bore 22a which accommodates the die means; that is, the axes of the bores 42a, 43a and 22a would not all lie in the same plane. The altered main housing with its appurtenances, may be attached to the upper arm 64 of the cartridge reloader 65 in any suitable way with the entrance member 30a of my device uppermost (Fig. 6). In such a structure, the cartridge reloader merely functions as a support for my device. Bullets are passed through the device so supported, by a punch 34a driven by a mallet or the like. In this form of the invention, the plungers 50a (Fig. 7) are rigidly connected by a bar or yoke 66 having a ram 67 attached to the medial portion thereof.

In the operation of this embodiment, bullets are passed downwardly by means of the punch to drive the bullet to the lubricating position, as illustrated in Figs. 2 and 5. Then the ram 67 is struck with the mallet and this will cause the grease to flow in spurts from opposite directions directly into the groove or grooves of the bullet.

Attention is directed to the yoke 66 which serves to move both plungers or pistons simultaneously when it is desired to force lubricant through the passageways controlled by the cones 45a. The modified form of the invention is simpler and less expensive to manufacture than the preferred form; and, the greasing is not automatic; but, the difficulty which is encountered by the compacting of grease within the die means is avoided. The ejection of bullets in both forms of the invention is entirely automatic as the bullets introduced into the mouth of the die means function to displace the processed bullets within the apparatus which fall through the exit and of the die means.

While I have disclosed, by way of example, the preferred forms of the invention, changes in construction and arrangement of parts thereof may be resorted to without departing from the field and scope of the same, and I intend to include in

this specification all such variations in the method and apparatus as fall within the scope of the appended claims.

What I claim and desire to secure by Letters Patent is:

- 5 1. An apparatus of the character described, comprising a body having at least three bores extending therethrough, die means positioned at least partially in one of said bores and forming an auxiliary bore through which a bullet may be forced axially to be compressed by the die means, said auxiliary bore being interrupted intermediate the ends thereof to expose the grooved portion of the bullet in a plane perpendicular to the axis of the bullet, relatively short ports placing the other bores of the body in communication with the bore containing the die means, where the auxiliary bore is interrupted, cylinders fixed to the body and communicating with said other bores, pistons cooperating with the cylinders for forcing lubricant therefrom, and adjustable valves mounted on the body, extending into said other bores and adapted to control the flow of lubricant from the cylinder to said ports.
- 10 2. An apparatus of the character described, comprising die means forming a bore through which a bullet may be forced axially, said bore being interrupted intermediate the ends thereof to expose the grooved portion of the bullet from all directions in a plane perpendicular to the axis of the bullet, and means arranged in close proximity to said bore for forcing lubricant simultaneously from opposite directions against the exposed portion of the bullet, the last-mentioned means comprising a relatively movable cylinder and piston, and braking means for yieldingly resisting relative movement of the cylinder and piston.
- 15 3. An apparatus of the character described, comprising a base having a cross bar forming abutment means, a frame having a lower end pivotally connected to the base at a point remote from said cross bar, and a bullet sizing and lubricating device pivotally connected to the upper portion of the said frame and having piston means abutting against the abutment means of the cross bar.
- 20 4. The combination with a cartridge reloader frame of the type having a plurality of spaced arms, of a body detachably mounted on one of said arms, said body having an intermediate bore and end bores, die means arranged at least partially in the intermediate bore and interrupted between its ends to permit lubricant to be applied to a bullet in the bore of the die means, ports placing the bores of the body in communication with one another, cylinders fixedly connected to the body and having inner ends extending into the end bores of the body, pistons extending into the cylinders, means rigidly connecting the outer ends of the pistons and adapted to be struck between the ends thereof for forcing the pistons into the cylinders, and adjustable valve members extending into the end bores of the body for controlling the flow of lubricant from the cylinders to the intermediate bore.
- 25 5. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.
- 30 6. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.
- 35 7. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.
- 40 8. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.
- 45 9. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.
- 50 10. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.
- 55 11. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.
- 60 12. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.
- 65 13. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.
- 70 14. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.
- 75 15. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body.

pistons extending into the outer end portions of the cylinders, and means connecting the outer ends of the pistons and having an anvil arranged between the ends of said connecting means.

6. In a device of the character described, a body having communicating intermediate and end bores which extend through the body, bullet sizing dies arranged at least partially within the intermediate bore and having portions spaced apart to permit communication between the end bores and the bore of the die means, cylinders having their inner ends extending into the end bores of the body and secured to said body, pistons extending into the outer end portions of the cylinder, means connecting the outer ends of the pistons and having an anvil arranged between the ends of said connecting means, and threaded valve members having threaded connection with the body and extending into the end bores for controlling the flow of lubricant from the cylinders to the intermediate bore.

7. A device of the character described, comprising a body having intermediate and end bores arranged in close proximity to one another, short ports in the body placing the bores in communication with one another, bullet grasping means removably associated with the intermediate bore and interrupted between its ends so that a bullet within the grasping means may have its grooved portion exposed to lubricant passing simultaneously through said ports, a pair of cylinder members having their inner ends extending into the end bores and secured to the latter, a pair of piston members extending into the cylinder members for forcing lubricant from the latter through said ports to the bullet within the grasping means, and means for simultaneously moving one pair of said members relatively to the other for forcing lubricant from the cylinder members.

8. A device of the character described, comprising a body having intermediate and end bores arranged in close proximity to one another, short ports in the body placing the bores in communication with one another, bullet grasping means removably associated with the intermediate bore and interrupted between its ends so that a bullet within the grasping means may have its grooved portion exposed to lubricant passing simultaneously through said ports, a pair of cylinder members having their inner ends extending into the end bores and secured to the latter, a pair of piston members extending into the cylinder members for forcing lubricant from the latter through

said ports to the bullet within the grasping means, means for simultaneously moving one pair of said members relatively to the other for forcing lubricant from the cylinder members, and threaded valve elements having threaded connection with the body and extending into the end bores for controlling the lubricant passing from the cylinder members to said ports.

9. An apparatus of the character described, 10 comprising a base, a plurality of piston members operatively connected to said base, a body having at least three bores therein, a plurality of cylinders cooperating with the piston members for feeding a lubricant into two of said bores, passageways placing the last two mentioned bores in communication with the third bore, means in the third bore for grasping a bullet while being lubricated, and means for mounting said body for relative movement between the body and base for causing lubricant from the cylinders to be forced simultaneously into the third bore.

10. Apparatus for sizing and lubricating grooved bullets comprising, means forming a bore through which a bullet may be forced axially, 25 said bore being interrupted intermediate the ends thereof to expose the grooved portion of the bullet from opposite directions in a plane perpendicular to the axis of the bullet, means arranged in close proximity to said bore for forcing lubricant simultaneously from a plurality of streams and in opposite directions against the exposed portion of the bullet, said last-mentioned means including a relatively movable cylinder and piston, said cylinder having a flared discharge passageway, and a substantially conical valve element movable into the passageway for controlling the flow of the lubricant from the cylinder to the grooved portion of the bullet.
